UNITED STATES PATENT OFFICE.

JOHN GABBOTT CARTMILL, OF LEAD, SOUTH DAKOTA.

MINE-SHOVEL.

1,078,255.

Specification of Letters Patent.

Patented Nov. 11, 1913.

Application filed October 5, 1912. Serial No. 724,141.

To all whom it may concern:

Be it known that I, JOHN C. CARTMILL, a citizen of the United States, residing at Lead, in the county of Lawrence and State of South Dakota, have invented a new and useful Improvement in Mine-Shovels, of which the following is a specification.

This invention relates to a mine shovel although it will of course be understood that the invention can be employed in excavating cuts, or removing banks or in handling piles of coal or ores, as its usefulness is not limited to mine work.

The invention consists in a truck adapted to travel upon a track and from which extends a slidable beam carrying a shovel, said beam being supported upon a steerable frame, and together with means for lowering and raising the shovel, sliding the beam forwardly and rearwardly, and conveying the matter collected by the shovel from the swinging frame to the rear of the truck where it is discharged into a suitable car.

The above is a brief outline of the device which will be hereinafter fully described, pointed out in the claims and which is shown in the accompanying drawings, in which—

Figure 1 is a side elevation of the complete device. Fig. 2 is an enlarged side elevation of the forward portion of the truck and parts carried thereby. Fig. 3 is an enlarged vertical section upon the line 3—3 of Fig. 1. Fig. 4 is an enlarged vertical section upon the line 4—4 of Fig. 1, looking toward the rear. Fig. 5 is an enlarged side elevation of the upper portion of the front frame. Fig. 6 is a horizontal section on the line 6—6 of Fig. 1. Figs. 7, 8, and 9 are details of a winding drum mechanism. Fig. 10 is a plan view of a truck frame showing a rack mounted thereon.

In these drawings, 1 represents a suitable truck, which travels immediately in advance of a suitable mine car 2. Mounted on the forward ends of the truck 1 are two uprights 3, said uprights being connected by a suitable cross piece 4. Upon the rear of the truck are similar uprights 5. Mounted upon the truck is a suitable motor 6 of any desired kind, and there is also mounted upon the truck, a suitable upright frame 7 and in said frame are journaled drums 8 and 9. The drum 9, which is the lower one, is provided with a suitable sprocket 10, and a sprocket

chain 11 runs from the motor over the said sprocket wheel. This drum carries also a suitable sprocket 12 and a sprocket chain 13 runs over the sprocket wheel 12 and also over a sprocket wheel 14 carried by the drum 8.

It will of course be understood that the term "drum" as used by me includes both the shaft and that particular enlarged portion upon which suitable cables are adapted to be wound.

Mounted transversely across the top of the truck is a shaft 15 which carries cog wheels 16. Rack bars 18 which form the lower members of the front frame are mounted upon said cog wheels and at their forward ends carry suitable uprights 19, the tops of which are connected by a cross member 20. Extending from the cross member 4 to the cross member 20 and secured to the undersides of said cross members, are channel beams 21, forming guides between which is slidably held a shovel supporting beam 22. The frame formed by the rack bars 18 and the uprights 19 and the guides 21 is supported at its front end by a suitable wheel 23, said wheel being adapted to be steered as will be hereinafter set forth.

Suspended from the front end of the slidable beam 22 by means of a cable 24 is a scoop or shovel 25 having a bail 26 to which the cable 24 is secured. This cable 24 travels over a small pulley 27 hung upon the underside of the forward portion of the slidable beam 22 and also over idlers 28 as most clearly shown in Fig. 5. After passing the last idler 28, the said cable travels down to and winds upon the drum 9 as shown in Figs. 2 and 4. This cable controls the raising and lowering of the shovel and in order to regulate the movement of the slidable beam between the guides 21, a second cable 29 is secured to the drum 9 and from said drum passes over a pulley 30 mounted upon the cross member 4 and thence runs forwardly over a pulley 31 mounted upon the forward cross member 20, and thence back to the rear end of the slidable beam to which it is connected by means of a suitable eye 32. The shovel is also connected to said beam at the rear end by means of a brace 33 and a link 34, the eye 32 being conveniently formed upon the upper end of said link as shown in Fig. 5.

The brace or shovel beam 33 is pivotally connected to a rearwardly extending bail 35

carried by the shovel as shown in Figs. 1 and 3.

In order that the material gathered by the shovel may be delivered into the car 2 a system of conveyers is provided as follows: A forward conveyer 36 receives the material from the shovel, the same being directed thereto by a suitably arranged apron 37 arranged between the lower part of the conveyer 36 and below the shovel, when the same is in dumping position, said apron being carried by two braces 38 of the front frame. From the conveyer 36 the material is conveyed by a discharge chute 39 upon a longer conveyer 40. This conveyer is off-set with respect to the truck 1 in order to clear the drums 8 and 9. At its upper end the conveyer 40 discharges into a second chute 41, which in turn discharges the material into the car 2. It will be understood that these conveyers may be of any suitable type adapted to handle the material being worked upon, and they are provided with any necessary supporting beams, and idlers. To drive said conveyers I provide a suitable shaft 42 and a sprocket chain 43 extends from the motor and runs over a suitable sprocket wheel 44 fixed upon one end of said shaft. Upon the other end of said shaft are sprocket wheels 45 and 46. A chain 47 runs from the sprocket wheel 45 to a sprocket wheel 48 mounted upon a shaft 49, and upon said shaft is also mounted a sprocket wheel 50 and a chain 51 runs from the sprocket wheel 50 over a sprocket wheel 52 mounted upon a shaft 53 upon which is also mounted a drum 54 over which the upper end of the conveyer 36 passes. A suitable sprocket chain 55 also runs from the motor over a suitable sprocket wheel 56, which drives the drum 57 over which the conveyer 40 travels at its upper end. The shaft 15 is provided with a gear wheel 58 which meshes with a suitable gear wheel 59 carried by a shaft 60 parallel to and to the rear of the shaft 15. The shaft 60 is provided with a sprocket wheel 61 over which runs a sprocket chain 62, which in turn runs over the sprocket wheel 46.

It will of course be understood that any desired arrangement of gearing may be employed for the purpose of driving the conveyers, and I have described in detail the form shown in order that the operation of the parts may be clear.

In order to steer the forward frame a suitable steering rod 63 is provided, which at its lower end carries a worm gear 64 meshing with a worm wheel 65 carried by the end of a shaft 66 upon which wind and unwind cables 67 connected to the pivoted axle 68 upon which the front wheels 23 are mounted. In order that the devices mounted upon the truck 1 may also be swung from side to side, I form said truck with an

upper platform 1^a. This portion is pivotally connected to the body portion of the truck adjacent its rear end by a king bolt 69. The front end of the platform 1^a rests upon a curved cog track 70 semi-circular in form, the details of which will be herein-after described.

While a particular form of drum mechanism is not essential I have considered it best to show and describe the preferred form. While 8 and 9 represent the complete drums the detail parts of a single drum are as follows: A spool 71 has a flange 72 on which works a hand brake 73. A depending frame 74 supports a shaft 75 to which is secured one end of the band. A lever 76 is mounted on the shaft and the opposite end of the band is secured to the lever. At the opposite end the spool engages a friction ring 77 fixed on the drum shaft 78 which is hollow and slotted at 79, the spool being slidable. The friction ring could be of any desired form but I recess its inner face and secure wooden blocks 80 thereto, and provide the face of the spool with a cut face to coöperate with the blocks—so the two faces will disengage automatically when released. To drive the spool to the ring I provide a thread box 81 in which works a screw 82. This enters the shaft 78 and engages a pin 83 which forces a block 84 against the spool 71 through slot 79, and holds same against the friction ring. The screw is rotated by a handle 85. The track 70 is carried by the car frame 1 and the rear of the platform 1^a rests on a circular plate 87 through the center of which the king bolt 69 extends. Suitable cog-wheels, not shown, support the front of the platform and travel on the rack portion 70^a of the trackway 70.

What I claim is:

1. The combination with a truck, of a frame mounted upon two front wheels, cog wheels mounted upon the truck, rack bars carried by the said frame and adapted to work upon said cog wheels, a shovel carried by said frame, means mounted upon the truck for controlling said shovel, and means carried by the frame and operable from the truck for steering the wheels of the frame.

2. A device of the kind described comprising a truck, a steerable frame, the rear end of which is loosely mounted upon and movable longitudinally with respect to the truck, guides carried by said frame, a beam slideable in said guides, a shovel suspended from said beam and means mounted upon the truck for regulating movement of the beam and rise and fall of the shovel.

3. The combination with a truck, a frame having its rear end movably mounted upon the truck, wheels supporting the front portion of said frame, a shovel supported from said frame, a conveyer arranged in said

frame and adapted to receive material from said shovel, a second conveyer carried by and to one side of the truck, and adapted to receive material from the first mentioned 5 conveyer, a chute adapted to discharge material from the second conveyer into a suitable car, and means mounted upon the truck for operating said shovel.

4. A device of the kind described comprising a steerable frame, a truck supporting the rear end of said frame, the frame being movable longitudinally with respect to said truck, guides carried by said frame, a beam 10 slidable between said guides, a pulley arranged at the front ends of said guides, a second pulley arranged at the rear ends of the guides, a drum mounted upon the truck, a cable having one end secured to the drum, said cable passing over said pulleys and thence 15 rearwardly from the first mentioned pulley to the rear end of the beam, and being secured to said rear end, a shovel, a second drum upon the truck, a cable having one end se-

cured to said second mentioned drum and the other end secured to the shovel and a 25 pulley secured to the forward portion of the beam, the last mentioned cable running over said pulley.

5. A device of the kind described comprising a truck, a frame, said frame comprising 30 rack bars, cog wheels mounted upon the truck, the rack bars of the frames resting upon said wheels, wheels supporting the front end of the frame, guides carried by the frames, a beam slidably mounted in said 35 guides, a shovel suspended from the forward portion of said beam, a brace secured to the rear portion of the beam pivotally connected to the shovel, drums upon the truck, and cables connected respectively to 40 said drums and to said beam and shovel.

JOHN CABBOTT CARTMILL.
